(57) **CLAIM**

The ornamental design for a euchre scoring block, as shown and described.

DESCRIPTION

FIG. 1 is a top, left side, front perspective view of the euchre scoring block, showing, in particular the ornamental design thereof; and,

FIG. 2 is a top plan view thereof.

The right side is a mirror image of the left side and rear side is a mirror image of the front shown in FIG. 1. The bottom surface does not form part of the claimed design.
